CLAIM

The ornamental design for a reflective strip, as shown and described.

DESCRIPTION

FIG. 1 is a front view of a first embodiment of a reflective strip showing our new design;

FIG. 2 is a top view thereof;

FIG. 3 is a left side view thereof;

FIG. 4 is a right side view thereof;

FIG. 5 is a bottom view thereof; and

FIG. 6 is a front view thereof, showing the reflective strip in an alternate position folded in half and fastened to a shirt pocket illustrating a preferred environment of use.

FIG. 7 is a front view of a second embodiment of a reflective strip showing our new design;

FIG. 8 is a top view thereof;

FIG. 9 is a left side view thereof;

FIG. 10 is a right side view thereof;

FIG. 11 is a bottom view thereof; and,

FIG. 12 is a front perspective view thereof, showing the reflective strip in an alternate position folded in half and fastened to a sleeve of a shirt illustrating a preferred environment of use.

The back views of the first and second embodiments of the reflective strip are unornamented and are not shown.

The broken lines depict portions of the reflective strip that form no part of the claimed design. Additionally the broken lines showing a shirt pocket in FIG. 6 and a shirt sleeve in FIG. 12 illustrate the environment of the claimed design and likewise form no part of the claimed design.
